UNITED STATES PATENT OFFICE.

ALLEN R. BARNETT, OF MERCER, MISSOURI, ASSIGNOR OF ONE-HALF TO ODUS ALLEN
MOORE, OF MERCER, MISSOURI.

CLAMPING DEVICE.

Application filed November 11, 1924. Serial No. 749,200.

To all whom it may concern:

Be it known that I, ALLEN RILEY BARNETT, a citizen of the United States, residing at Mercer, in the county of Mercer and State of Missouri, have invented certain new and useful Improvements in Clamping Devices, of which the following is a specification, reference being had to the accompanying drawings.

10 This invention relates to certain improvements in clamping devices and has relation more particularly to a device of this general character for maintaining a box lid in applied position and it is an object of the 15 invention to provide a device of this kind embodying novel and improved means whereby the same may be readily and conveniently operated.

Another object of the invention is to provide a novel and improved device of this general character which is adapted to engage a box body and the box lid or cover for effectively holding such lid or cover in applied position and which device when applied also provides means whereby the box 25 may be readily handled.

The invention consists in the details of construction and in the combination and arrangement of the several parts of my improved clamping device whereby certain important advantages are attained and the device rendered simpler, less expensive and otherwise more convenient and advantageous for use, as will be hereinafter more fully set 35 forth.

The novel features of my invention will hereinafter be definitely claimed.

In order that my invention may be the better understood, I will now proceed to describe the same with reference to the accompanying drawings, wherein:—

Figure 1 is a view in perspective illustrating a clamping device constructed in accordance with an embodiment of my invention and in applied position;

Figure 2 is a vertical sectional view taken through the structure as illustrated in Figure 1;

Figure 3 is a fragmentary view in perspective of the upper end portion of the lever.

My invention as herein disclosed is particularly adapted for use in connection with an egg case and as disclosed in the accom-

panying drawings, B denotes the box body 55 part of such case or the like which is provided along the upper margin of each of its end walls 1 with a ledge or shoulder 2. Coacting with the box body part is a box cover or lid C of a conventional type. 60

My improved clamp comprises an elongated member 3 angular in cross section and which when applied, has one flange a overlying the adjacent end portion of the cover or lid C and with its second flange b overlying the adjacent end wall 1 above the ledge or shoulder 2.

At its central portion the flange b has secured thereto and depending therefrom a plate 4 having its lower marginal portion 70 provided with an outstanding arcuate rack 5. The upper end portion of the plate 4 is provided with an extension plate 6 formed to overlie the upper portion of the plate 4 to provide a supporting bracket. 75 Secured to and bridging the space between the plate 4 and the bracket 6 is a rivet or pin 7 with which is pivotally connected an end portion of a rock arm 8, said rock arm being arcuate in form and extending 80 beyond opposite sides of the pin or rivet 7. The inner end portion of the rock arm 8 is bifurcated and extending within the resultant kerf 9 is an end portion of an arm 10 the same being pivotally connected by the 85 pin or rivet 11. This arm 10 extends downwardly with respect to the plate 4 and is provided with an inwardly disposed jaw 12 which extends through the vertically disposed slot 14 produced in the plate 4. This 90 jaw 12 is adapted to engage from below the ledge or shoulder 2 so that upon upward movement of the arm 10 the device in its entirety will effectively clamp and hold the end wall 1 of the box body part and the adjacent end portion of the box cover or lid C.

The outer end portion of the arm 8 is provided with an angular extension 15 provided along one marginal portion with a lip 16 which is adapted to engage the rack 5 100 whereby the device may be effectively locked in desired clamping position. This lip 16 may be readily disengaged from the rack 5 by exerting slight outward or lateral movement to the extension 15.

The flange b of the member 3 at opposite sides of the plate 4 has hingedly connected therewith, as at 17, the extremities

of a bail or handle 18 whereby when in applied position provides convenient and effective means for manipulating the case.

Normally the bail or handle 18 is in its low-
5 ermost position so as to afford no hindrance or obstruction to the stacking of cases to which devices constructed in accordance with my invention may be applied.

From the foregoing description it is thought to be obvious that a clamping device constructed in accordance with my invention is particularly well adapted for use by reason of the convenience and facility with which it may be assembled and operated,
10 and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

25 1. In combination with a container provided with a ledge and a cover for said container, a member angular in cross section, one flange of which being adapted to overlie an end portion of the cover and the second flange to overlie the container above the ledge, and means carried by the member to engage the ledge whereby the cover may be clamped to the container, said means being entirely below the flange adapted to overlie the cover.

2. In combination with a container provided with a ledge and a cover for said container, a member angular in cross section, one flange of which being adapted to overlie an end portion of the cover and the second flange to overlie the container above the ledge, a plate depending from the member, a lever pivotally supported by the plate, and an arm in pivotal connection with the lever and provided with a jaw to engage the ledge from below upon movement of the lever in one direction, and means for holding the lever against movement in the opposite direction.

3. In combination with a container provided with a ledge and a cover for said container, a member angular in cross section, one flange of which being adapted to overlie an end portion of the cover and the second flange to overlie the container above the ledge, a plate depending from the member, a lever pivotally supported by the plate, an arm in pivotal connection with the lever and provided with a jaw to engage the ledge from below upon movement of the lever in one direction, and means for holding the lever against movement in the opposite direction, said lever and arm being positioned outwardly of the plate, said plate being provided with a slot through which the jaw of the arm extends to engage the ledge.

In testimony whereof I hereunto affix my signature.

ALLEN R. BARNETT.
